UNITED STATES PATENT OFFICE.

GEORGE BRAY, OF BLACKMAN LANE, LEEDS, COUNTY OF YORK, ENGLAND.

GAS-REGULATOR.

SPECIFICATION forming part of Letters Patent No. 333,823, dated January 5, 1886.

Application filed September 29, 1885. Serial No. 178,534. (No model.) Patented in England May 22, 1885, No. 6,307.

To all whom it may concern:

Be it known that I, GEORGE BRAY, a subject of the Queen of Great Britain and Ireland, and residing at Blackman Lane, Leeds, in the county of York, England, have invented certain new and useful Improvements in Gas-Regulators, of which the following is a specification.

My invention consists of certain improvements in that class of gas-regulators which are to be applied to gas pipes or mains to regulate the flow of gas, and to prevent the pulsations caused by the working of gas-engines or similar devices from affecting the pressure, as more fully described hereinafter.

In the accompanying drawings, Figure 1 is a side view, partly in section. Fig. 2 is a view at right angles thereto, and also partly in section. Fig. 3 is a section on the line 1 2, Fig. 1; and Figs. 4 and 5 illustrate, in sections at right angles to each other, a modified form of valve.

The valve-case A is in communication with the gas-service pipe B coming from the main, and is immovable by being attached to an immovable part of the bag or reservoir, or otherwise. As shown in the drawings, it is attached to the pipe B and the part C', which forms one of the ends of the expanding and contracting bag, bellows, or reservoir C. The case A is divided, along its whole length, into two compartments, A' A'', by a plate, a, in which is a long slit, a''. One of these compartments (that A') is closed at both ends, and the other (that A'') is closed at the outer end, and in the other end of this second compartment the valve D works, and from this end of this second compartment the gas is supplied to the bag or reservoir. The gas passes into the bag or reservoir through the aforesaid slit a'' when the valve D does not close it. The area of the slit, when fully open, is large enough to pass an ample supply of gas for the engine or other consumer.

To the valve D is attached a spindle, d, connecting it with a movable part of the bag or reservoir. It is shown in the drawings as being attached to the cover c of a tube, c', on the movable end of the bag or bellows C, this tube allowing of the bellows closing, the internally-projecting part of the casing A entering this

tube c'. Owing to the gas entering the bag or reservoir C the valve D is drawn forward in its compartment A'' of the case, thereby reducing the area of the slit a'', through which the gas can enter the bag or reservoir.

I prefer to time the closing of the valve D so that it takes place before the pressure of the gas inside the bag or reservoir exceeds that of the surrounding atmosphere, except to the small extent required to open the bag or reservoir, and this whatever may be the pressure in the service pipe and main.

By thus supplying the engine or other consumer with gas at a practically-constant pressure I secure a regularity of charge, and thereby prevent waste and irregularity in the working of the engine or other apparatus, and to a great extent reduce the jumping of the lights on the same main due to the variation of pressure resulting from taking in the charges of gas from the bag or reservoir. Some variation of pressure, and consequent jumping of lights, would be caused by the valve D moving as often and to the same extent as the movable end of the bag or reservoir; but to prevent this I make the spindle d of the valve capable of a certain amount of movement independently of the valve, which may be effected by passing the spindle loosely into or through the valve and fixing on the said spindle two stoppers, d' and d'', so arranged that the spindle can be moved backward and forward for some distance without moving the valve. By this means, when the quantity of gas taken into or out of the bag or reservoir is not being greatly varied by the requirements of the gas-engine or other consumer, the pulsations of the bag or reservoir occur without moving the valve, and consequently without disturbing the gas in the service pipe and main.

The valve-case A may be attached to the service-pipe and to the bag or reservoir in a similar manner to the valve-case, shown in Fig. 1. On the upper side of the interior of the valve-case there is the channel a' for the gas, the said channel extending from the service-pipe to near the outlet end of the case, which passes into the bag or reservoir. The part of the valve D next the inside of the bag or reservoir is conical, and the other end of the valve fits the interior of the valve-case, and is suf-

ficiently heavy to balance the conical end of the valve. The valve is connected to the movable end of the bag or reservoir, and is moved in a similar way to that hereinbefore described.

5 As the valve is drawn forward, its thick end gradually closes the gasway, and when it is pushed back the gasway is gradually widened.

The gas is supplied to the engine or other consumer from the bag or reservoir through a 10 pipe passing through the fixed end of the bag or reservoir in any convenient position, but by preference below the valve-case.

In the drawings I have shown at E the pipe for the withdrawal of the gas from the bag C, 15 which bag I have shown as provided with a runner, F, mounted upon a rail or rod, f, extending from the pipe B; but it is to be understood that the details of construction can be greatly varied without departing from the 20 nature of my invention.

I claim—

1. The combination of the collapsible reservoir of a gas-regulator and gas-pipes with a

casing having a narrow long slot and a sliding valve controlled by said collapsible reservoir. 25

2. The combination of the gas-pipes, and collapsible reservoir, and a casing having a long narrow slot, with a sliding valve connected to the collapsible part of the reservoir, but leaving a play between the same, as and for the 30 purpose set forth.

3. The combination of the gas-pipes and casing having an opening, and a valve adapted thereto, with a collapsible reservoir carrying a spindle, d, passing through said valve and 35 provided with stops d' and d''.

In testimony whereof I have signed my name to this specification in the presence of two subscribing witnesses.

GEORGE BRAY.
